UNITED STATES PATENT OFFICE

171,444

EGG FRIER

Robert L. Gervais, Coos Bay, Oreg.

Application August 25, 1953, Serial No. 26,577

Term of patent 14 years

(Cl. D44—1)

To all whom it may concern:

Be it known that I, Robert L. Gervais, a citizen of the United States, residing at Coos Bay, county of Coos, and State of Oregon, have invented a new, original, and ornamental Design for an Egg Frier, of which the following is a specification; reference being had to the accompanying drawing, forming a part hereof.

Figure 1 is a perspective view of an egg frier showing my new design;

Figure 2 is a top plan view thereof;

Figure 3 is an end elevational view thereof; and

Figure 4 is a cross sectional view taken along the line 4—4 of Figure 1.

I claim:

The ornamental design for an egg frier, as shown.

ROBERT L. GERVAIS.
